UNITED STATES PATENT OFFICE

123,750

DESIGN FOR A COMBINED ASH TRAY AND CIGARETTE DISPENSER

Brian E. Cartwright, Marfa, Tex.

Application June 19, 1940, Serial No. 93,103

Term of patent 3½ years

To all whom it may concern:

Be it known that I, Brian E. Cartwright, a citizen of the United States, residing at Marfa, in the county of Presidio and State of Texas, have invented a new, original, and ornamental Design for a Combined Ash Tray and Cigarette Dispenser, of which the following is a specification, reference being had to the accompanying drawings, forming part thereof.

Figure 1 is a perspective view of a combined

ash tray and cigarette dispenser showing my new design.

Figures 3 and 4 are vertical sectional views taken substantially on the lines 3—3 and 4—4, respectively, of Figure 2.

I claim:

The ornamental design for a combined ash tray and cigarette dispenser, as shown.

BRIAN E. CARTWRIGHT.
